UNITED STATES PATENT OFFICE.

HENRY C. WEEDEN, OF BOSTON, MASSACHUSETTS, ASSIGNOR TO THE WEEDEN SANITARY MANUFACTURING COMPANY, OF RHODE ISLAND.

FLUSHING DEVICE.

SPECIFICATION forming part of Letters Patent No. 416,131, dated November 26, 1889.

Application filed February 20, 1889. Serial No. 300,528. (No model.)

To all whom it may concern:

Be it known that I, HENRY C. WEEDEN, of Boston, in the county of Suffolk and State of Massachusetts, a citizen of the United States, 5 have invented certain new and useful Improvements in Flushing Devices for Urinals and Similar Structures, of which the following is a specification.

My present invention relates to that class 10 of devices for flushing the bowls of urinals and kindred structures in which a flushing-tank is employed having an electrically-controlled discharge-valve, and in which the actuation of the discharging apparatus is effected by electricity. Its object is to so construct and arrange such an apparatus in combination with the bowl to be flushed that the operation of flushing shall be produced automatically whenever the bowl is used and by reason of 15 its use.

In the accompanying drawings I have represented a device for this purpose in the form now best known to me.

Figure 1 represents in elevation and partial 25 section a front view of the apparatus, and Fig. 2 a detail view of a portion thereof. Figs. 3 and 4 show modifications of a portion of the apparatus, as will be hereinafter more fully explained.

30 In the drawings, A represents a flushing-tank of well-known construction, the discharge of which for the purpose of flushing is effected by means of a lever B, carrying the armature C of an electro-magnet D, which lever is connected to and operates the discharge-valve E of the tank.

F is the flushing-pipe, which leads to and introduces the flushing-water into the article to be flushed, which I have represented at G 40 in the form of a urinal-bowl of ordinary construction.

The electro-magnet is connected in the ordinary manner with an electric battery H or other suitable source of electricity, and the 45 wires which form the path of the current are represented at I. At some convenient point I place the terminals of these wires I I, and in the drawings I have represented them as located in the discharge-pipe close to its junction with the urinal. As represented in the drawings, the device is intended to operate on the open-circuit principle—that is to say, the

circuit is normally open, and is to be closed only when the flushing operation is to take place.

I so construct, form, and locate the terminals J J' of the wires I I that they shall be normally separated when the apparatus is at rest or not in operation, but so that the introduction of fluid into the urinal by reason of 55 its use will cause one of the terminals before mentioned to be brought into contact with the other. When this is done, the circuit is completed, the flushing-valve is lifted, and the operation of flushing is thereby automatically 60 produced. For conveniently carrying out this method of operation I make one of the terminals J so that it shall be movable and shall be moved by the introduction of fluid into the urinal when used. I also so arrange the other 70 terminal J' relative to this movable terminal that when the latter is so moved by the fluid the two shall be brought in contact, as before described. This may be conveniently done by forming the terminal J of a thin flap (see 75 Fig. 2) hinged at its upper end and hanging normally by gravity in a position clear of the second terminal J', but in close proximity to it, and also across the path of the fluid coming from the urinal, so as to be moved thereby 80 into electrical connection with the terminal J when the urinal is used. It will be seen, however, that the precise construction and location of this movable terminal, so that it may be moved automatically by the fluid contents 85 of the urinal, may be widely varied without departing from the spirit of my invention. For example, as shown in Fig. 3, an enlargement of the discharge-pipe may be provided where it joins the urinal, as represented at L, 90 within which the two terminals J J' may be located. In this modification the movement of the terminal J to close the circuit and start the flush is obtained by attaching it to a tilting spoon-shaped lever M, the bowl of the 95 spoon being located within the path of the fluid as it comes from the urinal.

At Fig. 4 is represented a second modification, wherein the bringing of the terminals together is effected by the use of a float carrying the movable terminal J, which float is disposed in a similar enlargement L of the discharge-pipe. The operation of this device is that the introduction of fluid from the urinal,

raising the water-level, carries the float, and consequently the terminal J, upward and into contact with the other terminal J'. As it is desirable for many reasons to do so, I have 5 represented the flushing-tank as provided with a siphon. Any other form of tank or water-supply may, however, be substituted in which the production of a flush can be obtained by electric action. I have, furthermore, described 10 and shown the device as working upon the open-circuit principle; but it is obvious that the closed-circuit principle may be used instead, the two terminals being in that case so arranged that they normally stand in contact 15 and that the action of the fluid contents of the urinal will separate them and break the contact. The location of the circuit-controlling device at the point shown in the drawings is desirable, because it is thereby hidden from 20 sight and protected from accident.

It is obvious that the wires I I and terminals J J' should be suitably insulated wherever they pass in contact with electrically-conductive substances—as, for example, the metal 25 of which the various pipes in the apparatus are ordinarily made.

Electrically-operated flushing-tanks have long been known and used which were operated by a push-button in the ordinary manner. Furthermore, I am aware that fluid has 30 heretofore been used to form a part of an electrical conductor, and thus to shut off a water-

supply. I make no claim herein to an electric tank or to any device whereby fluid is used to shut off water.

I make no claim herein to any method of operation, the same being set forth in an application numbered 303,758 filed by me March 18, 1889.

I claim—

In combination, a flushing-tank, a bowl to be flushed therefrom, a flushing-pipe extending from the tank to the bowl, a valve controlling the outflow of water from the tank through the flushing-pipe, an electro-magnet, an armature therefor adapted to be moved when the magnet is energized, a connection between the armature and the valve, whereby said motion of the armature is adapted to raise the valve, an electric circuit including the said 45 electro-magnet, and a pair of terminals for said circuit located within the path of fluid introduced into the bowl from without, one of said terminals being movable and adapted to be moved into contact with the other by the 50 impact of the said fluid upon the said movable terminal, all substantially as set forth.

In testimony whereof I have hereunto subscribed my name this 12th day of February, A. D. 1889.

HENRY C. WEEDEN.
